UNITED STATES PATENT OFFICE.

ROBERT MALCOM, OF CHICAGO, ILLINOIS.

HELMET.

1,378,255.

Specification of Letters Patent. Patented May 17, 1921.

Application filed February 24, 1919. Serial No. 278,629.

To all whom it may concern:

Be it known that I, ROBERT MALCOM, a citizen of the United States, residing at Chicago, Cook county, State of Illinois, have 5 invented certain new and useful Improvements in Helmets, of which the following, taken in connection with the drawings, is a description.

My invention has for its object the production of a helmet, or head protector, 10 designed more particularly to be worn by those persons engaged in welding, or similar occupations, where it is necessary to protect the eyes of the wearer from extreme heat and brilliant light, as well as dust and other flying particles.

A further object of the invention is to provide such a device which is easily placed in position or removed, and one which will protect both the eyes and the head of the 15 wearer.

A further object of my invention is to provide such a head protector of material which is noninflammable, and nonheat conducting, 20 and which when in use rests upon the shoulders of the wearer, protecting the head and eyes from the heat and the eyes from the effects of the brilliant lights.

A further object of my invention is to provide a device of the class described, which 25 has means for ventilation, and which is provided with independent sets of glasses or lenses, which may be of different colors, and one set of which is detachable with respect 30 to the other, and for the purposes later described.

A further object of my invention is to provide a protector of this kind, which will prevent any light or reflections of light 35 reaching the eyes from the sides or back of the protector, or through cracks, or other openings around the lens holding frame.

Other objects of the invention will be apparent to those skilled in the art.

In the drawings I have illustrated what I 40 now consider the preferred form of my invention, although it is obvious certain changes may be made without departing from the spirit of the same, and in these 45 drawings,

Figure 1 is a front elevation of the helmet;

Fig. 2 is a side elevation of the same;

Fig. 3 is a bottom plan view, and

Fig. 4 is an enlarged sectional detail taken 50

on line 4—4, of Fig. 1, and showing in dotted lines a frame of the helmet when raised.

Referring to the drawings, number 5 represents the body portion of a head protector, 60 which may preferably be approximately semi-cylindrical, or semi-elliptical in form, or any shape to fit the contour of the back of the head of the wearer and leave room for the device to extend down to the shoulders 65 and be supported thereon when worn, and to fully protect the neck and upper chest from extreme heat.

This shell or protector body may be formed 70 of a single piece of material pressed into the desired form, which material is preferably, although not necessarily, fiber; or said protector may be constructed of a plurality of assembled parts forming the shell of the protector. When two or more parts are 75 assembled, they may be riveted together as shown by the rivets 6.

The frame portion 7 of the helmet is preferably constructed to present a plain surface, which lends itself more readily to the 80 eye protector forming a part of my invention.

An opening is cut through the front of the holder at a point directly in front of the eyes of the wearer. This opening may be of 85 any suitable size and shape, such as round (which I have shown in the drawings), elliptical, square, rectangular, or otherwise.

The lens holding frame 8 fits closely into this opening and is secured to the body 7 by 90 rivets, screws, or the like. This frame is preferably formed in halves, each having a shoulder 9 which abuts the inner wall of the opening, as shown more clearly in Fig. 4. A groove 10 is formed on the inside of 95 this lens holding frame 8. A glass or lens 11 fits into this groove and by closing the two halves of the frame around and securing them to the body of the protector, the transparent member 11 is held firmly in place. 100

Fitting around the outside of the frame 8 is another frame 12, which is movably secured to the body 7, in this instance, by a hinge 13 engaging it at the top of the frame. At a point exactly opposite the hinge member 105 is a boss or projection 14, formed integrally with the frame 12, which engages a spring member 15, which in turn is fixedly secured to the body 7 of the protector. The purposes of this will be hereafter explained. 110

This frame 12 is provided with shoulders 16 upon which is placed the 2nd transparent member 17, which may be glass, or any other suitable material. This transparent member 5 is held removably in place by detachable clips 18', which are secured to the edge of the frame 12 by screws, rivets, or the like. These clips are easily drawn over the edge of the transparent member 17 to hold it in 10 place, or to reverse the position of the same and remove the member 17 when necessary to replace or change said member.

Secured to the body portion 7 above the opening for the eyes are spring members 18, the front ends of which are brought into operative engagement with the movable frame 12 heretofore described. This frame 12 is provided at the hinged portion thereof with outwardly extending lugs 19, Fig. 2, 20 one of which engages each of the spring members 18. These spring members tend normally to hold the frame 12 in open position as shown in dotted lines in Fig. 4.

When worn, and the hinged member 12 is 25 in the open position, the eyes of the wearer are protected by the inner member 11, which is sufficient under some circumstances, but from the extreme heat of furnaces, or the like, the double protection is necessary, and 30 the wearer then lowers the hinged member until the lug 14 engages the member 15 which locks it in closed position with the protection of the double glass or protector in front of the eyes.

35 As will be observed, this outer frame 12 falls very closely around the inner frame 8, so that when in closed position no rays of light or light reflections can pass between these two frames and dull or blind the wearer's vision. The transparent member held in the movable frame 12, is of a color contrasting with the color of the inner glass. Thus the user may open or close the outer frame 12, as required, by disengaging the 40 frame 12 from the spring member 15, when necessary for a clearer examination of his work, or for any other reason, without removing the helmet.

When the frame 12 is disengaged from the 50 spring member 15, the action of the spring 18 curves the frame 12 to the position shown in the dotted lines in Fig. 4. When the wearer wishes to close the frame, he simply pushes it down to engage the boss 14 in the 55 opening provided for that purpose in the spring member 15.

60 By the use of this device it will be observed that when placed over the wearer's head, it is completely protected from the extreme heat of a welding furnace, or the like, and also from the brilliant light; that the user can easily and quickly close the frame 12 as he 65 needs to examine his work; that either or both of the transparent members are always in the line of vision of the work being done; that

the protector can be put on and removed without any loss of time or inconvenience to the wearer.

I claim:

1. A helmet or head protector comprising 70 a shell or casing, shaped to fit around the head and contact with the shoulders of the wearer, said casing having an opening therein in front of the eyes of the wearer, a lens-holding frame secured to said casing around said opening, a transparent member held therein, a frame surrounding said lens-holding frame and movably secured to said casing, and a transparent member removably secured to said last named frame. 75

15 2. A helmet or head protector comprising a casing formed of a single piece of non-inflammable material shaped to fit around the head and rest upon the shoulders of the wearer, said casing having an opening in 80 front of the eyes of the wearer, a frame surrounding said opening being fixedly secured in said casing, a transparent member secured in said frame, a frame movably secured to said casing, and surrounding the first mentioned frame, a transparent member removably secured in the last mentioned frame, means for holding said last mentioned frame and transparent member in open position, and means for holding it in closed position. 85

20 3. A helmet comprising a casing, adapted to fit around the head and rest upon the shoulders of the wearer, said casing having an opening in front of the eyes of the wearer, a transparent member closing said opening, 90 a frame member secured to said casing and surrounding the aforesaid transparent member, shoulders formed on said last mentioned frame, a transparent member of a contrasting color to the first mentioned transparent member positioned upon said shoulder and removably attached thereto, spring members attached to said casing and to said movable frame adapted to hold said frame in open position, and means for holding said frame 95 in closed position. 100

25 4. A helmet comprising a casing, adapted to fit around the head and rest upon the shoulders of the wearer, said casing having an opening in front of the eyes of the wearer, a transparent member closing said opening, 105 a frame member secured to said casing and surrounding the aforesaid transparent member, shoulders formed on said last mentioned frame, a transparent member of a contrasting color to the first mentioned transparent member and positioned upon said shoulder, removably attached thereto, and means for holding said frame in different adjusted positions with respect to and independent of 110 said first mentioned transparent member. 115

30 5. A helmet comprising a body portion fitting around the head and resting upon the shoulders of the wearer, said body portion having ventilating openings near the bottom 120 125 130

thereof, the top of said helmet being open, double eye protecting lenses positioned in front of the eyes of the wearer, one of said lenses being held in a frame stationary with respect to said helmet, and the other lens held in a movable frame, independent means for raising said last mentioned lens member above the range of vision through the stationary lens, and means for lowering said last mentioned lens in a plane parallel with the stationary lens, and securing it in that position.

6. A helmet comprising a body portion formed of a single piece of material fitting around the head and resting upon the shoulders of the wearer, said body portion having ventilating openings provided near the bottom thereof, double eye protecting trans-

parent members positioned in frames arranged in front of the eyes of the wearer, 20 one of said transparent members being stationary with respect to said helmet and the other movable, said last mentioned transparent member having a frame adapted when in closed position to inclose the rim of 25 the stationary transparent member and exclude all light between said members, substantially as described.

In testimony whereof I have signed this specification in the presence of two subscribing witnesses.

ROBERT MALCOM.
